UNITED STATES PATENT OFFICE.

EDWIN CROWLEY, OF MINNEAPOLIS, MINNESOTA.

GATE-LATCH.

1,099,489.

Specification of Letters Patent. Patented June 9, 1914.

Application filed February 10, 1913. Serial No. 747,393.

To all whom it may concern:

Be it known that I, EDWIN CROWLEY, a citizen of the United States, residing at Minneapolis, in the county of Hennepin and State of Minnesota, have invented certain new and useful Improvements in Gate-Latches; and I do hereby declare the following to be a full, clear, and exact description of the invention, such as will enable others skilled in the art to which it appertains to make and use the same.

My invention has for its object to provide an efficient gate latch especially designed for use in connection with double swinging gates and which may be operated from either side of the gate to release said gate and permit the same to open in advance of a person passing through the gate opening.

To the above ends, generally stated, the invention consists of the novel devices and combinations of devices hereinafter described and defined in the claims.

The invention is illustrated in the accompanying drawings, wherein like characters indicate like parts throughout the several views.

Referring to the drawings: Figure 1 is a view in side elevation of a double swinging gate mounted in a gate opening and hinged to one of the gate posts, the other gate post having secured thereto two of my improved gate latches, connected for simultaneous actions, some parts of the gate being broken away; Fig. 2 is a vertical section taken on the line $x^2 x^2$ of Fig. 1; Fig. 3 is a front side elevation of one of my improved gate latches, on an enlarged scale, also showing the latch lug in vertical section, taken on the line $x^3 x^3$ of Fig. 4; and Fig. 4 is a view principally in vertical section, taken on the line $x^4 x^4$ of Fig. 3.

The numerals 1 and 2 indicate a pair of tubular metallic gate posts located one on each side of a gate opening. A gate 3 is mounted in said gate opening and connected to the gate post 2, for double swinging movement, by hinges 4. As shown, the frame of the gate 3 is constructed from tubing, to which is secured a panel 5 of woven wire fabric.

In the drawings, an unusually high gate has been illustrated and is locked, at its upper and lower ends, to the gate post 1 by two of my improved gate latches, which are connected, for simultaneous movements.

These gate latches are identical in construction, but are secured to the gate post 1 in reverse order. An ordinary sized gate, of course, will require only one of the improved gate latches.

Referring now to one of the improved gate latches, the numeral 6 indicates a latch bracket adjustably and frictionally clamped onto the gate post 1 by a pair of horizontally extended and vertically spaced clamping bands 7. Said latch brackets 6 and clamping bands 7 are secured one to the other by draw bolts 8 passed through co-incident perforations in lugs 9 on the latch bracket 6 and lugs 10 on the clamping bands 7. At its lower end, the latch bracket 6 terminates in a laterally and horizontally projecting flange 11, which is provided, at its ends, with outwardly and downwardly curved cam surfaces 12. The latch bracket 6 is also provided with a horizontally projecting stop lug 13, spaced vertically above the flange 11. A latch lug 14 is adjustably secured, by a bolt 15, to the front vertical member of the frame of the gate 3, and is arranged to pass between the flange 11 and stop lug 13, during the swinging movement of the gate 3. When the gate 3 is closed, the latch lug 14 projects between the flange 11 and the stop lug 13. Obviously, the flange 11 will prevent the gate from sagging, and the stop lug 13 will prevent the gate from being lifted by hogs or other small animals in attempts to pass thereunder. The cam surfaces 12 serve to guide the latch lug 14 onto the flange 11.

Slidably mounted on the front vertical face of the latch bracket 6 is a latch plate 16, having, on its back, a laterally projecting lug 17, mounted for vertical movement in a recess 18, formed in the latch bracket 6. The lug 17 is held for straight line vertical movements by a pin 19 passed through the recess 18 and a perforation 20 in the lug 17, and mounted, at its ends, in seats 21 and 22, formed in the latch bracket 6, respectively, above and below the recess 18. A coiled spring 23 is mounted on the pin 19 and compressed between the lug 17 and the upper end portion of the recess 18, and tends to hold the lug 17 in engagement with the bottom of the recess 18.

In the lower intermediate portion of the latch plate 16 is formed a lock notch 24

that embraces the stop lug 13, and, when the gate is in a closed position, the latch lug 14, thus locking the gate. Integrally formed with the latch plate 16, on either side of the lock notch 24, is a pair of reversely projecting lugs 25, each provided with a perforation 26, the purpose of which will presently appear. The lower edges of the lugs 25 are formed with cam surfaces 27, which extend outwardly and upwardly from the lock notch 24, as best shown in Fig. 3. Under the swinging movement of the gate 3, its latch lug 14 engages either one of the cam surfaces 27, depending on which way the gate is moving, and lifts the latch plate 16, against the tension of its spring 23, a sufficient distance to permit the latch lug 14 to pass under the stop lug 13. In this position the engaged cam surface 27 is released from the latch lug 14 and the latch plate 16 is again returned to normal position, under the tension of its spring 23, with the latch lug 14 embraced by the lock notch 24.

Extending parallel with the front face of the latch plate 16 is a horizontally extended latch actuating lever 28, intermediately fulcrumed to a bolt 29, passed through an elongated vertically extended slot 30, formed in the latch plate 16 and having screw threaded engagement with the latch bracket 6. As best shown in Fig. 4, this bolt 29 extends through the seat 21 just above the pin 19 and locks said pin in position. The ends of the lever 28 are provided with finger pieces 31. Additional finger pieces 32 are integrally formed with the intermediate edge portions of the lock plate 16 and are located directly under the finger pieces 31. The top or upper edge of the latch plate 16 is provided with a laterally projecting flange 33, which overlies and rests upon the upper edge of the lock actuating lever 28. This flange 33 normally holds the latch actuating lever 28 in its normal or intermediate position. By pressing either set of finger pieces 31 and 32 toward each other, the latch actuating lever 28 is rocked on its fulcrum 29, thereby lifting the latch plate 16 against the tension of its spring, as best shown by dotted lines in Fig. 3. This lifting of the latch plate 16 carries the lock notch 24 above the latch lug 14, thereby releasing the same and permitting the gate to be opened in either direction. By providing the improved latch with reversely projecting pairs of finger pieces 31 and 32, the latch may be opened from either side of the gate, thus permitting the gate to swing away from the person opening the gate. Secured to each end of the flange 11, for swinging movement, is a lock link 34 adapted to be turned upward and over the lugs 25, thereby holding the latch plate 16 down or in its operative position.

To positively lock the links 34 to the lugs 25, ordinary padlocks may be inserted through the perforations 26 in said lugs 25.

When the improved gate latch is secured to a wooden gate post, the clamping bands 7 may be dispensed with and lag screws 76 passed through the perforated lugs 9 and into the wooden post.

Referring now to the double arrangement of gate latches, as shown in Figs. 1 and 2, the uppermost latch is turned in a reverse direction from the lowermost, and their gate actuating levers 28 are connected, for simultaneous movements, by a pair of parallel vertically extended rods 35. The ends 75 of these rods 35 are bent laterally and extended through perforated lugs 36, formed on the levers 28 on opposite sides of their fulcrums, and secured in position by pins 37. Obviously, when one of the latch actuating levers 28 is operated, like movement 85 will be imparted to the other lever.

What I claim is:

1. The combination with a pair of gate posts and a double swinging gate mounted 90 in the gate opening and hinged to one of the gate posts, of a latch bracket secured to the other of said gate posts and having a cam flange and a stop lug vertically spaced, the latter above the former, a spring-held 95 latch plate mounted on said latch bracket and having a lock notch embracing the stop lug on said latch bracket, said latch bracket also having cam edges projecting in opposite direction from said lock notch, a latch lug on said gate arranged to pass between the cam flange and stop lug of said latch bracket and to be held therebetween by the lock notch of said latch plate, said latch lug arranged to engage one or the other of said 100 cam edges, according to the direction of the movement of the gate, to thereby move said latch plate against the tension of its spring, reversely projecting latch-actuating 105 finger pieces on said latch plate, a latch-actuating lever intermediately fulcrumed to said latch bracket and terminating at its ends in finger pieces, and a projection on said latch plate engaging said latch lever and tending to yieldingly hold the same in 110 an intermediate position, substantially as described.

2. The combination with a pair of gate posts and a double swinging gate mounted 115 in the gate opening and hinged to one of the gate posts, of a latch bracket secured to the other of said gate posts, a spring held latch plate mounted on said latch bracket and having a lock notch and provided with cam edges projecting in opposite direction 120 from said lock notch, a latch lug on said gate adapted to be embraced and held by the lock notch of said latch plate, said latch lug arranged to engage one or the other of said cam edges, according to the direction of 125 13

the movement of the gate to thereby move said latch plate against the tension of its spring, and means including a link, for positively locking said latch plate in an operative position, substantially as described.

3. The combination with a pair of gate posts and a double swinging gate mounted in the gate opening and hinged to one of the gate posts, of a latch bracket secured to the other of said gate posts, a spring held latch plate mounted on said latch bracket and having a lock notch and provided with cam edges projecting in opposite direction from said lock notch, a latch lug on said gate adapted to be embraced and held by the lock notch of said latch plate, said latch lug arranged to engage one or the other of said cam edges, according to the direction of the movement of the gate to thereby move said latch plate against the tension of its spring, perforated lugs projecting from opposite sides of said latch plate, and links pivoted to said latch bracket and arranged to be turned over said perforated lugs, to positively lock said latch plate in an operative position, substantially as described.

20 4. The combination with a pair of gate posts and a double swinging gate mounted

in the gate opening and hinged to one of the gate posts, of a latch bracket secured to the other of said gate posts and having a cam flange and a stop lug laterally spaced one from the other, a spring held latch plate mounted on said latch bracket and having a lock notch embracing said stop lug, said latch plate also having perforated lugs projecting in opposite directions from said lock notch, said lugs having cam edges, a latch lug on said gate adapted to be embraced and held by the lock notch of said latch plate, said latch lug arranged to engage one or the other of said cam edges, according to the direction of the movement of the gate to thereby move said latch plate against the tension of its spring, and links pivoted to said cam flange and arranged to be turned over said perforated lugs, to positively lock said latch plate in an operative position, substantially as described.

25 In testimony whereof I affix my signature in presence of two witnesses.

EDWIN CROWLEY.
